(57) **CLAIM**

The ornamental design for a stacking set of cookware, as shown and described.

DESCRIPTION

FIG. 1 is a perspective view of a stacking set of cookware showing my new design;

FIG. 2 is a first side view thereof;

FIG. 3 is a second side view thereof;

FIG. 4 is a third side view thereof;

FIG. 5 is a fourth side view thereof;

FIG. 6 is a top view thereof;

FIG. 7 is a bottom view thereof; and,

FIG. 8 is an exploded side view thereof showing the individual set pieces.

The claim design is directed to an assembled set of cookware as shown in FIGS. 1-7, any deviations from the sides not shown forms no part of the claimed design.

1 Claim, 4 Drawing Sheets

FIG. 1

FIG. 2

FIG. 6

FIG. 7
